DESIGN FOR A DRESSING TABLE

Dorothy Jeanne Bower, Brooklyn, N. Y.

Application December 11, 1935, Serial No. 60,013

Term of patent 3½ years

To all whom it may concern:

Be it known that I, Dorothy Jeanne Bower, a citizen of the United States, residing in Brooklyn, county of Kings, and State of New York, have invented a new, original, and ornamental Design for a Dressing Table, of which the following is a specification, reference being had to the accompanying drawing, forming part thereof.

In the drawing, Fig. 1 is a top plan view of a dressing table showing my design;

Fig. 2 is a view in front elevation of the dressing table of Fig. 1; and

Fig. 3 is a view in side elevation of the dressing table of Figs. 1 and 2.

The illustrated dressing table embodying the invention comprises a body portion which con-

sists of spaced columns surmounted by an upper body portion. The table also includes a top combined with the columns and the body portion to produce a distinctive design, the top being substantially co-extensive in width with the body through its central portion but including rounded enlarged end portions which extend forwardly beyond the front and laterally beyond the ends of the table body.

The right end of the dressing table is of the same appearance as the left end shown in Fig. 3.

I claim:

The ornamental design for a dressing table substantially as shown and described.

DOROTHY JEANNE BOWER.
